CONTAINER

John E. Robinson, Glen Ellyn, and Richard P. Bigger, Lombard, Ill., assignors to American Can Company, New York, N. Y., a corporation of New Jersey

Application February 28, 1941, Serial No. 381,182

8 Claims. (Cl. 229—3.5)

The present invention relates to fibre containers or cans which are especially adapted for holding lard, hydrogenated shortenings, vegetable and mineral oils and similar materials and has particular reference to a composite multiple ply fibre container body which has an inner liner of fibrous material treated to make it oil and grease resisting or oil and grease proof and is glued to the inner wall of the body with a special oil resisting glue.

For a number of years attempts have been made to provide a satisfactory and economical fibre container for the holding of lard, vegetable and mineral oils and many and various structures of can bodies have been proposed for this purpose. The oil resisting properties of a liner for the inside of such a fibrous body must be of such a nature as to prevent seepage of any of the oily product into the fibrous walls of the can body layers. Over a period of time this type of product becomes very penetrating and unless the interior lining and the wall structure prevent any seepage of the oily product, such cans are not satisfactory.

The present invention relates to a special kind of fibre can body and when such a body becomes a part of a container for holding the oily product under consideration, metallic ends have been found to be satisfactory. These ends when properly applied to the fibre body prevent any loss of the oily contents by seepage at the end seams. Accordingly, the present invention is particularly directed to the construction of a multiple layer fibrous container body in which the respective layers are held together by a water base adhesive. An inner liner of fibre is also preferably used and such a liner is secured to the inner wall of the body preferably by an improved high grade glue specially treated so that it will readily bond the two surfaces together. Such an inner liner is also treated to give it maximum oil resisting properties.

An object of the present invention is the provision of an oil and grease-proof can formed with a laminated or spirally wound body of fibrous material such as chipboard and one having its multiple walls secured together by a water base adhesive together with an impregnated oil resisting fibrous liner, which is glued down with a special oil resisting adhesive.

Another object of the invention is the provision of a can of the character described having metal ends applied in a manner to insure an oil leak-proof joint between the fibrous body and the end.

Numerous other objects and advantages of the

invention will be apparent as it is better understood from the following description, which, taken in connection with the accompanying drawing discloses a preferred embodiment thereof.

Referring to the drawing:

Figure 1 is a longitudinal sectional view of an oil-proof container embodying the present invention and illustrating a multiple wall fibrous body with metal ends secured in closed position and completely enclosing an oily product such as lard, vegetable or mineral oil; and

Fig. 2 is an enlarged sectional detail illustrating a cross section of the fibrous body and showing an inner liner and an outer label.

In the drawing, the fibre body is designated generally by the numeral 11 and this body is provided with a suitable metallic bottom or end member 12 secured to the lower end of the body in a crimped joint 13. After the contents A have been filled into the can it is closed by a metallic top or end member 14 which may be crimped as at 15 to provide a leak-proof joint between the body wall and the top.

The fibre body 11 is composed of a plurality of layers or plies 21 (Fig. 2) the drawing illustrating two such layers. Such a body may be wound on a mandrel to provide the usual spiral construction or may be convolutely wound. In either event the multiple layer construction results, the layers being held together by a cement or adhesive 22.

The can body is preferably also provided with an inner liner of fibrous material 23 which has been specially treated and which is held in place against the inner wall of the inside layer 21 of the fibre body by a layer of special adhesive 24. It is also desirable to designate the contents of the can and for this purpose a label 25 may be secured around the outer wall of the fibrous body by an adhesive film 26.

The special adhesive layer 24, used to glue the liner to the first ply, is preferably formed of a high grade glue which may be an animal glue or other suitable glue which has been dispersed in water containing one per cent of a wetting agent. Such a wetting agent is preferably a sodium salt of a sulphonated diethyl ester of a dibasic acid such, for example, as sodium salt of monosulphonated diethyl ester of succinic acid. Other wetting agents may be used as, for example, a sodium salt of an alkyl phosphoric acid.

In forming this mixture, the glue and the wetting agent may first be dispersed in water. A suitable liquid hydrocarbon may then be added to the glue dispersion in water, and an emulsion

of the hydrocarbon in the glue and water may thereby be formed. An aromatic liquid hydrocarbon has been found satisfactory such as toluene ($C_6H_5CH_3$) or benzene (C_6H_6). A chlorinated aliphatic hydrocarbon may also be used, such as chloroform, carbon tetrachloride or beta trichloroethane or the di-tri- or tetra-chloride of ethylene. The hydro-carbon, or halogenated hydrocarbon is incorporated with the glue to provide a softening agent for the wax-impregnated inner liner 23, so that a more satisfactory bond will result between the liner, and the next ply of the fibre body.

In making up this adhesive according to one satisfactory formula, the hydrocarbon used is taken as substantially equal to about thirty percent of the weight of the dry solids. This adhesive may be applied directly to the body stock on the body winder in the usual manner.

The inner liner is preferably formed of a high grade sulphite paper which is impregnated under heat and pressure with approximately twenty percent of an oil-proof wax made by hydrogenating castor oil, cottonseed oil, soya bean oil, peanut oil, fish oil or similar materials. The adhesive film 22 used to hold the body layers together need not be the same as that in layer 24, in fact any simple water base glue such as those derived from dextrine, starches, casein, or animal glue may be used. These glues may be applied in any suitable manner as directly on the winding machine when the can bodies are formed. This inner liner is lapped sufficiently to make a satisfactory joint, the lap being held together by the adhesive used for uniting the liner with the body wall.

The varnished label 25 is preferably applied in the usual manner on the formed can body. The film of adhesive 26 used for securing the label to the body may be the same adhesive as is used in the formation of the can body or any other water base glue. Such a label will be applied with a slight overlap and this completes the formation of the can body.

The formed can body then receives its bottom end 12. In order to prevent fraying of the end of the can body when it is secured to the flange of the bottom member the lower edge of the body is preferably flared outwardly slightly as at 31 (Fig. 1).

To provide the joint 13 such an end member 12 may be formed with an inner flange wall part 32, which is slightly inclined downwardly and outwardly as shown, and an outer flange wall part 33. This outer wall part may be crimped inwardly to tightly engage the flared part 31 of the fibre body to provide the joint 13.

If desired, a sealing film 34 may be applied to the outwardly flanged end 31 of the can body prior to applying the can end member 12. Such a sealing mixture may be formed of a suitable wax or other oil resisting material and is disposed on the inner bottom edge of the can body so that it contacts directly with the flange wall part 32 of the end. When this sealing mixture has been tightly squeezed into the joint 13, the container is ready to receive its contents.

The upper end member 14 may be suitably formed to engage the upper edge of the can body 11. Since it is desirable to remove the top repeatedly after opening the can the construction of the top end preferably differs somewhat from that of the bottom end member. As illustrated in Fig. 1, such a top may be formed with an inner flange wall part 35 and an outer flange wall

part 36 between which a sealing channel 37 is provided. The flange wall part 36 is preferably extended so that it will engage the body wall in a frictional area and preferably terminates in a curled edge 38.

Prior to applying such a top end, the body wall may be flared outwardly slightly as at 39. This makes it so that the top may be more easily applied both for its initial sealing position and later as a reclosure. In applying this top member the flared section 39 of the can body 11 enters into the sealing channel 37 of the flanged top and the flanged walls 35, 36 may be squeezed together if desired, to provide a suitable sealed joint between the can body and the top. In some cases a sealing material may be desirable for this upper joint the same as for the bottom joint 13 in which case a wax sealing substance may be applied to the inner top edge of the can body as a sealing film 41.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. An oil-proof fibre container for lard, vegetable and mineral oil and the like, comprising a container body having a plurality of fibre layers held together with an adhesive, and an inner liner of sulphite paper impregnated with hydrogenated castor oil, said liner being secured to the inside body wall by a glue which has been dispersed in water with a sodium salt of a sulphonated diethyl ester of a dibasic acid and with a liquid hydrocarbon.

2. An oil-proof container for lard, vegetable and animal oils, and the like, comprising a container body having a plurality of fibre layers held together with an animal glue, an inner liner of sulphite paper impregnated with hydrogenated castor oil, said liner being secured to the inner body wall with an adhesive comprising an animal glue which has been dispersed in water with a sodium salt of a sulphonated diethyl ester of a dibasic acid and a liquid aromatic hydrocarbon, and metallic end members secured to the ends of said body in sealing engagement with said inner liner.

3. An oil-proof fibre container for lard, vegetable and mineral oils and the like, comprising a container body having a plurality of fibre layers held together with an adhesive consisting of a glue which has been dispersed in water containing about one percent (1%) of a wetting agent and into which a hydrocarbon solvent in amount approximating thirty percent (30%) of the weight of the dry solids in said adhesive is incorporated, and an inner oil-proof liner of sulphite paper impregnated with oil-proof wax secured to the inner wall of the body by said glue.

4. An oil-proof fibre container for lard, vegetable and mineral oils and the like, comprising a container body having a plurality of fibre layers held together with an adhesive derived from animal glue, and an inner liner of sulphite paper impregnated under heat and pressure with an oil-proof wax of hydrogenated oil, said liner being secured to the inside layer of said body by an adhesive consisting of a glue which has been dispersed in water with a sodium salt of a sul-

phonated dioctyl ester of a dibasic acid and a hydrocarbon solvent to the extent of about thirty percent (30%) of the weight of the dry solids.

5. An oil-proof fibre container for lard, vegetable and animal oils and the like, comprising a container body having a plurality of fibre layers held together with a water base adhesive, and an inner liner of a sulphite paper impregnated with an oil-proof wax of hydrogenated cotton-seed oil, said liner being glued down with an adhesive consisting of an animal glue which has been dispersed in water with a sodium salt of a monosulphonated dioctyl ester of succinic acid and with a liquid chlorinated aliphatic hydrocarbon.

6. An oil-proof fibre container for lard, vegetable and mineral oils and the like, comprising a container body having a plurality of fibre layers held together with an adhesive consisting of an aqueous dispersion of an animal glue and starch, and an inner liner of sulphite paper impregnated with an oil-proof wax of hydrogenated fish oil, said liner being secured to the body wall by means of an adhesive consisting of an aqueous dispersion of a glue to which is added a sodium salt of an alkyl phosphoric acid and a liquid aromatic hydrocarbon.

10

25

7. An oil-proof fibre container for lard, vegetable and mineral oils and the like, comprising a container body having a plurality of fibre layers held together by a water base adhesive, an inner liner of fibrous material impregnated under heat and pressure with an oil-proof wax derived from a hydrogenated vegetable oil and an oil resisting adhesive between the innermost layer of said container body and said inner liner for securing them together, said oil resisting adhesive comprising an animal glue dispersed in water, a wetting agent and a hydrocarbon solvent.

8. An oil-proof fibre container for lard, vegetable and mineral oils and the like, comprising a container body having a plurality of fibre layers held together by a water base adhesive, an inner liner of fibrous material impregnated under heat and pressure with an oil-proof wax derived from a hydrogenated animal oil and an oil resisting adhesive between the innermost layer of said container body and said inner liner for securing them together, said oil resisting adhesive comprising an animal glue dispersed in water, a wetting agent and a hydrocarbon solvent.
